BUBBLE CAP ASSEMBLY

Edward D. Rapisarda, Agawam, and Harry F. Tapp, Longmeadow, Mass., assignors to Gilbert & Barker Manufacturing Company, West Springfield, Mass., a corporation of Massachusetts

Original application February 12, 1949, Serial No. 76,132. Divided and this application August 27, 1949, Serial No. 112,734

2 Claims. (Cl. 261—114)

1

This invention relates to improvements in bubble cap assemblies, such as are used in fractionating towers and the like for the purpose of intimately contacting a gas with a liquid.

This application is a division of our application Serial No. 76,132, filed February 12, 1949, now Patent No. 2,491,209, granted December 13, 1949.

The invention has for an object the provision of an improved bubble cap assembly which is adapted for quantity production manufacture at low unit cost and which enables the chimney and cap to be readily mounted on the floor of a tray of the bubble tower and secured thereto by the hold down bolt, working from a position above the tray or deck, and which enables easy removal of the cap and chimney, leaving the tray or deck free of protuberances or other obstructions to facilitate cleaning of the deck.

Another object of the invention is to provide a bubble cap assembly of improved construction to enable the chimney to be mounted in or demounted from, a gas escape opening in the floor plate of the bubble tray and, when mounted therein, to be clamped in leak-proof fashion to the floor plate, the construction being characterized in that the floor plate, which may be of thin metal, is clamped between a shoulder on the outer peripheral wall of the chimney and an anchor ring fixed to the bottom of the plate, the shoulder extending completely around the periphery of the chimney and the ring having a similar peripheral shape and extent, whereby clamping pressure may be applied to press the plate against the shoulder at all points in the periphery of the latter.

Another object of the invention is to provide an anchor ring for the purpose described of novel construction enabling economical manufacture.

These and other objects of the invention will best be understood from the following detailed description of one illustrative example of the invention in the accompanying drawings, in which:

Fig. 1 is a top plan view of a bubble cap assembly embodying the invention;

Fig. 2 is a sectional elevational view taken on the line 2—2 of Fig. 1;

Fig. 3 is a sectional plan view taken on the line 3—3 of Fig. 2;

Fig. 4 is a cross sectional view taken on the line 4—4 of Fig. 3; and

Figs. 5 and 6 are perspective views of two of the parts of the anchor ring prior to assembly.

2

Referring to these drawings; 1 represents a portion of the floor or deck of a bubble tray, which, as is well known, is adapted to be mounted in a bubble tower. A plurality of these trays are mounted in the tower at different levels, in the general manner disclosed in Patent No. 1,667,136 to Alexander, granted April 24, 1928. It is desirable that the floor plate 1 be made of non-corrosive metal, such as stainless steel for example, and, since this metal is relatively expensive, the floor plate is made as thin as feasible. In each bubble tray are mounted many of the bubble cap assemblies, which form the subject matter of this invention. All parts of each bubble cap assembly are preferably made of non-corrosive metal, such as stainless steel for example. A single one of these assemblies will be described herein.

Each bubble cap assembly includes a chimney 2 (Fig. 2) rising from the floor plate 1 of the bubble tray and conducting through it the gas or vapor, which rises from below the plate. Seated on top of the chimney in vertically spaced relation is a bubble cap 3, which deflects the rising gas or vapor, forcing it downwardly and causing it to pass through liquid, which is maintained on the tray as disclosed in said patent to a level indicated by the dot-dash line 4. The chimney 2 may be of any suitable cross sectional shape, although it is herein shown (Fig. 3) as cylindrical. This chimney (Fig. 2) has a shoulder 5 thereon which extends entirely around its external periphery, is spaced from its lower end, and is located in a plane at right angles to the vertical axis of the chimney. The lower end of chimney 2 is seated in an opening 6 of like cross sectional shape in the floor plate 1 with the shoulder 5 abutting the upper surface of the plate. The shoulder 5 may be conveniently formed by rolling a bead 7 in the chimney.

The cap 3 has generally the shape of an inverted bowl. It is supported from the top of chimney 2, and spaced from the upper end thereof, by means of a plurality (three as shown) of horizontal vanes 8 (see also Fig. 1) which are fixed to the top wall of the cap and located inside the same. These vanes extend from a position near the center of the cap radially outward in diverging relation to and beyond the chimney 2, having notched outer ends (Fig. 2), providing on each a horizontal seat 9 to rest on top of the chimney and a vertical shoulder 10 to lie inside the same. These shoulders serve to locate the cap 3 approximately coaxially of chimney 2. Each vane is fixed in any suitable way to the cap. As

shown, each vane 8 may have two projections 11, which extend upwardly through slots in the top of the cap and are held thereto by "staking," as indicated.

The bubble cap 3 and chimney 2 are held together and to the floor plate 1 of the bubble tray by means of a bolt and nut connection between the cap 3 and an anchor ring which underlies the floor plate. The anchor ring is designated 12. It has the same cross sectional shape as the chimney 2 (Fig. 3), in this case circular, and its upper end affords an annular seat which is located in a plane at right angles to the vertical axis of the ring and which abuts the lower face of the floor plate 1 at all positions around its periphery. This ring may be held to the floor plate in any suitable way. For example, the ring (Fig. 2) may have projections, such as 13 and 14, which extend through slots in the plate 1 and are staked, as indicated in Fig. 3, to hold the ring against the under side of the plate. The anchor ring has a cross bar 15 (Figs. 3 and 4), carrying a nut 16 (Figs. 2 and 4) to receive a bolt 17, which is passed through a central hole in cap 3 (Fig. 2) and extends downwardly through the chimney with its lower end threaded into the nut. The head of the bolt 17 engages the top of cap 3 and is operatively engaged with the chimney through vanes 8 to draw the chimney and anchor ring together. When the bolt 17 is tightened the cap 3 and chimney 2 are drawn together and the chimney is drawn downwardly until the floor plate 1 is tightly clamped against the shoulder 5 and the anchor ring 12. An annular area of the floor plate is thereby clamped against the shoulder 5 to provide a leak-tight joint. The engaged portions of plate 1 and shoulder 5 are parallel and are drawn into close contact. The clamping area extends completely around the periphery of the engaged parts, preventing bending of the thin floor plate, such as might occur intermediate the clamped points, if as has heretofore been common practice, a spider with angularly-spaced radiating arms is used in place of the continuous anchor ring. The anchor ring 12 may have a series of angularly-spaced holes 18 therein to enable greater freedom of flow into the lower end of chimney 2.

The anchor ring however is constructed of a single strip of material rolled up into cylindrical form with its ends abutting, as clearly shown in Fig. 5. Upstanding one from each abutting end of this strip are two projections 14, which abut each other, and diametrically opposite these abutting projections 14, is a single projection 13 of twice the width of a projection 14. The two projections 14, when abutting, are adapted to pass through and closely fit one of the slots in floor plate 1 (Fig. 3) and the projection 13 is adapted to pass through the other slot and be staked to hold the anchor ring to the floor plate. The projections 14 when thus engaged are held against separation and thus the two ends of the ring are maintained in abutment. The anchor ring also has diametrically opposed pairs of slots 19 (Fig. 5) to receive projections 20 formed on the ends of a cross bar 15, herein shown in Fig. 6 as made in channel form. Suitably fixed, as for example by the welding indicated in Fig. 4, to the cross bar 15, at a location centrally between its ends, is the nut 16. The cross bar may have suitable holes therein, such as 22, (Figs. 3, 4 and 6) to yield greater freedom of flow into the lower end of chimney 2.

To assemble the cross bar in ring 12, the latter is pressed together at two diametrically opposite points, each located about centrally between the projections 13 and 14. This makes the ring slightly elliptical and enough so to enable the cross bar 15 to be slipped into place. The projections 20 at one end can be slipped into their slots 19 and then with the other projections 20 aligned with their slots 19, pressure on the ring can be relaxed, allowing the second pair of projections 20 to enter their slots 19 and the ring to resume its normal shape. The cross bar 15 will then be held firmly in place. After the described assembly has been made the ring 12 is mounted on plate 1 and the projections 13, 14 are engaged in their slots and secured as described. When these projections are engaged in the slots in plate 1, the ring is prevented from being spread in the direction necessary to cause disengagement of the projections 20 from their slots 19. The anchor ring 12 and its cross bar 15 can thus be easily and quickly assembled without the use of any tools and without welding.

It should be noted that welding or mechanically working the metal impairs its non-corrosive properties and to restore these properties it is necessary to anneal the metal. Consequently, it is desirable to avoid such welding or working of the metal wherever feasible.

With this invention, the chimney of the bubble cap assembly is demountable from the floor plate 1, when required, and it is also firmly clamped in leak tight fashion to this floor plate, which usually is of thin metal, such as stainless steel, or other suitable non-corrosive metal. The floor plate is held between a shoulder on the chimney and an anchor ring with a clamping area which extends completely around the periphery of the engaged parts, avoiding bending of the thin metal away from the shoulder of the chimney, which would occur if for example a spider with radiating arms were used in place of the continuous ring. This result is secured with a simple structure which is capable of economical manufacture. The anchor ring can be formed economically from two metal stampings and a standard nut which is welded in place in one of the stampings. The stamped out parts can be easily and quickly assembled without the aid of tools and the assembly mounted on and secured to the floor plate in the simple manner described.

What is claimed is:

1. A bubble cap assembly for covering an opening in the floor plate of a bubble tower tray and comprising in combination, a floor plate provided with an opening, a chimney having its lower end engaged in said opening and rising from said floor plate, a cap supported by the upper end of the chimney, said chimney having a shoulder extending completely around its outer periphery in a plane at right angles to the vertical axis of the chimney, an anchor ring composed of a single strip bent into closed loop form with its ends in abutment and having slots at two opposite points in its periphery, said ring having substantially the same cross sectional shape as said chimney and fixed to the under side of said plate and encircling said opening in closely adjacent relation, a cross bar extending across said ring and having on its ends projections which are engaged in said slots, a nut carried by said cross bar, and a bolt engaged in said nut and with said cap for holding together the cap, chimney, plate and ring with the plate clamped between said ring and shoulder.

2. A bubble cap assembly for covering an opening in the floor plate of a bubble tower tray and comprising in combination, a floor plate provided with an opening, a chimney having its lower end engaged in said opening and rising from said floor plate, a cap supported by the upper end of the chimney, said chimney having a shoulder extending completely around its outer periphery in a plane at right angles to the vertical axis of the chimney, an anchor ring composed of a single strip bent into closed loop form with its ends in abutment, upstanding projections on said ring one at each of the abutting ends and abutting each other, another projection upstanding from the ring at a point opposite from the two abutting projections, said plate having slots therein in one of which the two abutting projections are received and in the other of which the third-named projection is received, said projections being fixed to the plate to hold the anchor ring thereto and also to prevent separation of the abutting ends of the ring, the latter having slots therein at least one at each of two opposite points on said ring which points are located one near the two abut-

ting projections and one near the third-named projection, a cross bar extending across the ring and having at each end at least one projection which is engaged with the adjacent slot in the ring to hold the cross bar to the ring, a nut carried by the cross bar, and a bolt engaged with said cap and threaded into said nut for holding together said cap, chimney, plate and ring with the floor plate clamped between said shoulder and

10 ring.
